UNITED STATES PATENT OFFICE.

EDWARD J. BROOKS, OF EAST ORANGE, NEW JERSEY.

SEAL.

Application filed January 27, 1922. Serial No. 532,195.

To all whom it may concern:

Be it known that I, EDWARD J. BROOKS, a citizen of the United States, and a resident of East Orange, in the county of Essex and

5 State of New Jersey, have invented certain new and useful Improvements in Seals, of which the following is a specification.

This invention relates to seals and is more particularly an improvement on the seal 10 shown in Patent No. 961,931 of June 21, 1910.

In that patent is shown an open-face seal formed by a cup-shape member, the cup-shape member having a closed bottom and 15 its walls constituting prongs or lips which are bent over the cord. With the construction there shown it has been found possible to insert a tool and to pry open the lips. The main object and feature of this 20 invention is to prevent the insertion of a tool, for this purpose, into the seal.

Fig. 1 is a general view of a seal embodying one form of the invention, the seal being shown in its closed position and with 25 the cord in place.

Fig. 2 is a sectional view on the plane of line 2—2 of Fig. 1.

The seal member 1 is cup-shape as shown

with a central opening 2 both in the back and front of face thereof, and the walls of 30 the cup-shape member form two pairs of opposed lips 3, 4, 5 and 6 arranged at right angle to each other and on the same side of the seal. After cord 7 has been placed in the seal the lips are folded or bent in- 35 wardly as shown in Figs. 1 and 2 and a filling member 9 is inserted in the central opening and pressed into shape to completely fill said opening to thereby prevent the insertion of a tool to pry lips 3, 4, 5 or 6 40 open.

I claim:

A seal part composed of a cup-shape member provided with a central opening in its front and back face, the walls of said member forming two pairs of opposed lips ar- 45 ranged at right angles to each other on the same side of the member, and a central filling member occupying the central opening to completely fill the same and thereby prevent the insertion of a tool for prying open the lips. 50

Signed at New York city in the borough of Manhattan, county and State of New York, this 26th day of January, 1922.

EDWARD J. BROOKS.
